ELECTRIC TANK HEATER CONTROL SYSTEM

Filed July 20, 1944

UNITED STATES PATENT OFFICE

2,387,180

ELECTRIC TANK HEATER CONTROL SYSTEM

Clark M. Osterheld, Stoughton, Wis., assignor to
McGraw Electric Company, Elgin, Ill., a corporation of Delaware

Application July 20, 1944, Serial No. 545,766

4 Claims. (Cl. 219—39)

My invention relates to electric heating and particularly to control systems for electric heaters of domestic hot water tanks.

Among the objects of my invention are the following: to provide a control system that shall effect immediate energization of the electric heater of a hot water tank after closing of a time-controlled switch at the start of an off-peak period in case a relatively large amount of hot water has been withdrawn from the tank during an on-peak period; that shall effect energization of the heater after closing of the time-controlled switch at the start of an off-peak period with a predetermined time period of delay in case a relatively small amount of hot water has been withdrawn from the tank during the on-peak period; and that shall continue energization of the heater, if necessary, until substantially all of the water in the tank has been heated to a predetermined high temperature, irrespective of the opening of the time-controlled switch at the end of an off-peak period.

In the drawing,

Figure 1 is a view in vertical section through an ordinary domestic hot water tank, having associated therewith a control system embodying my invention, and,

Fig. 2 is a diagram of connections embodying my invention.

Referring first of all to Fig. 1 of the drawing, I have there shown an ordinary domestic hot water tank 11, having a lower cold water inlet pipe 13, an upper hot water outlet pipe 15, and being surrounded by a mass 17 of heat insulation, which heat insulation is held in proper operative position around the tank 11 by an outer casing 19.

I provide preferably, but not necessarily, a single electric heater 21, which may be of the clamp-on type and which is located around the bottom end portion of tank 11 in a tunnel 23. It may be here pointed out that all of the above mentioned details form no part of my present invention and are all well known in the art.

I provide a lower thermally-actuable heater control switch, designated by numeral 25, and I have shown this as including a tubular member 27, having a closed inner end and having its outer open end secured in an opening in tank 11 in a fluid-tight manner. An expansion rod 29 is located in tube 27 and is adapted to have its outer end engaged with and be disengaged from a block 31 of electric-insulating material mounted on the outer free end of a contact arm 33, which is of substantially resilient construction and has located thereon a contact member adapted to en-

gage with and be disengaged from a cooperating contact member on a substantially rigid contact arm 35. The two contact arms are supported on tank 11 as by blocks 37 of electric-insulating material. The design, construction, and adjustment of the thermally-actuable heater control switch 35 is such that when tube 27 is surrounded by cold water, the length of expansion rod 29 will be such that it will be out of engagement with electric-insulating block 31, so that the two contact arms 33 and 35 will be in electric-conducting engagement with each other. When tube 27 is surrounded by hot water, the length of expansion rod 29 will be such that the contact on contact arm 33 will be out of engagement with the contact on contact arm 35. When I speak of cold water, I mean water, the temperature of which is on the order of 60° to 70° F., or thereabouts; and when I speak of hot water, I mean water, the temperature of which is on the order of 150° F., or slightly higher.

Referring now particularly to Fig. 2 of the drawing, I have there shown a diagram of connections embodying a particular construction of thermal retarder, which is designated generally by numeral 39. The thermal retarder 39 is preferably located in heat-receiving relation on a tank at substantially the mid-height thereof. It includes a first thermal switch which is normally closed when subject to cold water and a second thermal switch which is normally open when subject to the temperature of cold and of hot water in the tank and is closed when its temperature is appreciably above that of hot water, say on the order of 250 F. or more. The general details of construction of the thermal retarder heater control switch unit 39 are shown in my copending application, S. N. 537,941, filed May 29, 1944, and assigned to the same assignee as is the present application.

The thermal retarder switch unit includes a first switch, having a bimetal bar 41, which has insulatedly mounted thereon a contact bridging member 43 adapted to engage with and be disengaged from two fixed contacts 45 and 47. A second bimetal bar 51 has mounted thereon at one end thereof a pair of pivot plates 49 which are adapted to be pivotally engaged by the sharpened ends of the first bimetal bar 41. The bimetal bars 41 and 51 are the two toggle arms of a snap-acting mechanism comprising an over center spring 53 located in aligned slots in the adjacent ends of the two bimetal bars. The outer end of the second bimetal bar 51 is rigidly supported. When bridging member 43 moves with a snap ac-

tion to open position, it will engage a stop member 54.

The second thermal snap-acting switch of the thermal retarder unit 39 includes a first bimetal bar 55 having mounted on one end thereof a contact bridging member 57 with suitable electric insulation therebetween. A second bimetal bar 59 has one end fixedly supported and is provided at its other end with a pair of pivot plates 49, which are adapted to be pivotally engaged by the sharpened ends of the first bimetal bar 55, and an over center spring 61 is positioned in two aligned slots in the adjacent ends of bimetal bars 55 and 59. The contact bridging member 57 is adapted to engage with and be disengaged from three fixed contacts 63, 65, and 67 and will engage a stop member 68 when moved with a snap action to open position. While I have shown the contacts 63, 65, and 67 generally only, it is to be understood that any means for insuring proper contact pressure between these contacts and the contact bridging member 57 will be employed in a manner well known in the art.

The design, construction, and adjustment of the first thermal retarder switch is such that the contact bridging member will be in engagement with fixed contacts 45 and 47 when subject to cold water in the tank and will be disengaged therefrom when subject to hot water in the tank. The second thermal switch of the thermal retarder switch unit, comprising particularly the bimetal bars 55 and 59, is so designed, constructed, and adjusted that the bridging member 57 will be out of engagement with the fixed contact members 63, 65, and 67 when subject to cold and to hot water in the tank and will be in engagement therewith when subject to a higher temperature, on the order of 250° F. or over. In order to obtain this appreciably higher temperature, I provide a heating coil 69, which may be insulatedly mounted on and supported by bimetal bar 55. In order to obtain the hereinbefore described operation, I may use heavier bimetal bars or bimetal bars which are not as highly thermally-responsive as are the bars 41 and 51.

I provide further a time-controlled switch, designated generally by numeral 71 and including a pair of contact arms 73 and 75, which are adapted to be held in engaging and electric-conducting position relatively to each other during off-peak periods of a twenty-four hour day by any continuously operative timing means now well known in the art. The contact arms 73 and 75 will be out of engagement with each other during all on-peak periods of a twenty-four hour day.

I provide a first supply circuit conductor 77 and a second supply circuit conductor 79. The first supply circuit conductor 77 is connected to contact arm 73, and the second contact arm 75 is connected by a conductor 81 with the first contact 45 of the first thermal retarder switch. The two fixed contacts 47 and 63 are connected by a conductor 83, which conductor is connected by a conductor 85 with one terminal of the heater 21, the other terminal of which is connected by a conductor 87 with contact arm 35 of the lower thermally-actuable switch 25. The other contact arm 33 of switch 25 is connected to the other supply circuit conductor 79 by a conductor 89. Contact 65 is connected by a conductor 91 with conductor 81 and by a conductor 93 with one terminal of heating coil 69, the other terminal of which is connected by a conductor 95 with contact arm 35. The third fixed contact 67 of the second thermal retarder switch is connected by a

conductor 97 with contact arm 73 and the first supply circuit conductor 77.

The design, construction, and adjustment of heating coil 69 insulatedly mounted on bimetal bar 55 is such that the relatively low-wattage translated therein into heat will cause temperature rise of bimetal bar 55 to a value on the order of 250° F. in say from four to six hours, and if desired, I may provide any means well known in the art to vary the watts translated into heat in heating coil 69, such as an adjustable rheostat.

Let it now be assumed that the system operated, as will be hereinafter described in detail, so that at the end of the off-peak period, during the late night hours and ending say at 6 a. m., the tank was full of hot water. Let it be further assumed that during normal use of hot water during the day, withdrawals of hot water from the tank were such as to cause the thermal retarder switch unit to be subject to cold water and contact bridging member 43 to be in engagement with fixed contacts 45 and 47 at say 10 p. m., which, for illustrative purposes, may be considered to be the start of the off-peak period, running through the late night hours. The closure of the time-controlled switch 71 at 10 p. m. will therefore cause immediate energization of heater 21 through a circuit substantially as follows: from supply circuit conductor 77 through engaged contact arms 73 and 75, conductor 81, through the engaged contacts 45 and 47 with bridging member 43, through a part of conductor 83, then through conductor 85 and heater 21, through conductor 87, then through the engaged contact arms 35 and 33 and through conductor 89 to the second supply circuit conductor 79. This is because of the fact, as has already been hereinbefore set forth, that the contact bridging member 43 of the first thermal retarder switch will be in engagement with the fixed contact members 45 and 47, if the thermal retarder switch unit is subject to cold water.

Heating coil 69 will also be energized through a circuit traceable as follows: from supply circuit conductor 77 through engaged contact arms 73 and 75, through conductors 81, 91, and 93, through heating coil 69, through conductor 95, through engaged contact arms 35 and 33, and then through conductor 89 to the second supply circuit conductor 79.

Under normal operating conditions, energization of heater 21 through the hereinbefore described circuit will continue for a length of time not to exceed two or three hours, depending upon the size of the tank as well as the heating capacity of electric heater 21. When sufficient water has been heated to a temperature on the order of 150° F. to affect the thermal retarder switch unit, the first thermal switch, including particularly bimetal bars 41 and 51, will be opened with a snap action, so that energization of the heater 21 will be discontinued after say two hours.

Energization of heater 69 will continue, and if it will require four hours to cause temperature rise of bimetal bars 55 and 59 to a value sufficient to cause closure of the second switch in four hours, deenergization of the heater 21 will continue for one hour, after which closure of the second thermal retarder switch will reenergize heater 21 through the following circuit: from supply circuit conductor 77 through engaged contact arms 73 and 75, through a part of conductor 81, through conductor 91, through engaged contacts 65 and 63 with contact bridging member 57, through a part of conductor 83, through con-

ductor 85 and heater 21, through conductor 87, then through engaged contact arms 35 and 33, and then through conductor 89 to the second supply circuit conductor 79.

Energization of heater 21 through the last above described circuit will continue until substantially all of the water in the tank is hot, when the lower thermally-actuable switch 25 will open because of being subject to hot water, with the result that both heater 21 and heating coil 69 will be deenergized. If it would require say three hours to heat up the rest of the water in the tank to a temperature of 150° F. within the off-peak period, the above described deenergization of heater 21 will be effected.

If, however, because of a demand for hot water in the late night hours, say from 4 to 5 or 6 o'clock a. m., some of the hot water is withdrawn, energization of heater 21 will be continued even after opening of the time-controlled switch 71 through a circuit substantially as follows: from supply circuit conductor 77 through conductor 91, through contacts 67 and 63 and bridging member 57, through a part of conductor 83, through conductor 85, heater 21, conductor 87, through engaged contact arms 35 and 33, and then through conductor 89 to the second supply circuit conductor 79. Thus, if because of unusual and unexpected calls for hot water, less than all of the water in the tank is hot at the time of opening of the time-controlled switch 71 at 6 o'clock a. m., energization of the heater 21 will continue beyond the end of the off-peak period, and the heater 21 will be deenergized by the lower thermally-actuable heater control switch 25, as has been hereinbefore described.

The thermal retarder disclosed in this application and the control system, including the thermal retarder heater control switch unit, are therefore effective to cause immediate energization of an electric heater of a domestic hot water tank upon closure of a time-controlled switch at the start of an off-peak period, and is also effective to cause energization of the electric heater with a predetermined time delay period after closure of the time-controlled switch in accordance with whether the thermal retarder switch is subject to cold water or to hot water at the time of closure of the time-controlled switch. The system is further effective to continue energization of the heater 21 beyond the opening of the time-controlled switch in case the lower thermally-actuable heater control switch is subject to cold water at the time of opening of the time-controlled switch.

Various modifications may be made in the system embodying my invention without departing from the spirit and scope thereof, and all such modifications coming clearly within the scope of the appended claims shall be considered as covered thereby.

I claim as my invention:

1. A control system for a domestic hot water tank having an electric heater, comprising a lower thermally-actuable heater control switch mounted in heat-receiving relation on a tank adjacent to the lower end thereof and adapted to be in closed position when subject to cold water in the tank and to be in open position when subject to hot water in the tank, a time-controlled switch adapted to be in closed position during off-peak periods and a thermal retarder heater control switch unit adapted to be mounted in heat-receiving relation on a tank intermediate the ends thereof and consisting of a first snap-acting ther-

mal switch having two fixed contacts and an open and a closed position, a second snap-acting normally open thermal switch having three fixed contacts and adapted to be moved into closed position when its temperature has reached a predetermined high value, a heating coil for said second switch for heating it to said predetermined high value and electric connections between said heater and said switches to cause immediate energization of said heater, through said lower switch, said time-controlled switch and the first switch of said thermal retarder switch unit after closure of said time-controlled switch in case said thermal retarder switch unit is subject to cold water at that time, the energization through said circuit continuing until the thermal retarder switch unit is subject to hot water, the energization of said heater being thereafter continued through said lower thermal switch and the second switch of said thermal retarder unit until terminated by said lower thermal switch when substantially all of the water in the tank is hot.

2. A control system for a domestic hot water tank having an electric heater, comprising a lower thermally-actuable heater control switch mounted in heat-receiving relation on a tank adjacent to the lower end thereof and adapted to be in closed position when subject to cold water in the tank and to be in open position when subject to hot water in the tank, a time-controlled switch adapted to be in closed position during off-peak periods and a thermal retarder heater control switch unit adapted to be mounted in heat-receiving relation on a tank intermediate the ends thereof and consisting of a first snap-acting thermal switch having two fixed contacts and an open and a closed position, a second snap-acting normally open thermal switch having three fixed contacts and adapted to be moved into closed position when its temperature has reached a predetermined high value, a heating coil for said second switch for heating it to said predetermined high value and electric connections between said heater and said switches to cause energization of said heater through said lower switch, said time-controlled switch and the second switch of said thermal retarder unit after a predetermined time delay period after closure of said time-controlled switch in case the thermal retarder unit is subject to hot water and the lower switch is subject to cold water at that time, the energization continuing through said lower switch and said second switch of the thermal retarder unit if less than all of the water in the tank is hot when the time-controlled switch is opened until the heater is deenergized by opening of the lower thermally-actuable switch when substantially all of the water in the tank is hot.

3. A control system for a domestic hot water tank having an electric heater, comprising a lower thermally-actuable switch adapted to be mounted in heat-receiving relation on a tank at the lower end portion and adapted to be in closed position when subject to cold water in the tank and to be in open position when subject to hot water in the tank, a time-controlled switch adapted to be in closed position during off-peak periods and a thermal retarder heater control switch unit adapted to be mounted on a tank intermediate the ends thereof and consisting of a first snap-acting thermal switch having two fixed contacts and adapted to be in closed position when subject to cold water in the tank and to be in open position when subject to hot wa-

ter in the tank, a second snap-acting switch having three fixed contacts and adapted to be in open position when subject to cold and to hot water in the tank and to be in closed position when subject to an appreciably higher temperature, a heating coil for said second switch for heating it to said appreciably higher temperature, the energization of said heating coil being controlled jointly by said lower thermally-actuable and said time-controlled switches and electric connections between said heater and said switch to selectively cause immediate energization of said heater upon closure of said time-controlled switch in case said thermal retarder unit is subject to cold water in the tank at that time and to cause energization of said heater a predetermined time period after closure of said time-controlled switch in case said thermal retarder switch is subject to hot water in the tank at that time.

4. A control system for a domestic hot water tank having an electric heater, comprising a lower thermally-actuable switch adapted to be mounted in heat-receiving relation on a tank at the lower end portion and adapted to be in closed position when subject to cold water in the tank and to be in open position when subject to hot water in the tank, a time-controlled switch adapted to be in closed position during off-peak periods and a thermal retarder heater control switch unit adapted to be mounted on a tank intermediate the ends thereof and consisting of

a first snap-acting thermal switch having two fixed contacts and adapted to be in closed position when subject to cold water in the tank and to be in open position when subject to hot water in the tank, a second snap-acting switch having three fixed contacts and adapted to be in open position when subject to cold and to hot water in the tank and to be in closed position when subject to an appreciably higher temperature, a heating coil for said second switch for heating it to said appreciably higher temperature, the energization of said heating coil being controlled jointly by said lower thermally-actuable and said time-controlled switches and electric connections between said heater and said switch to selectively cause immediate energization of said heater upon closure of said time-controlled switch in case said thermal retarder unit is subject to cold water in the tank at that time and to cause energization of said heater a predetermined time period after closure of said time-controlled switch in case said thermal retarder switch is subject to hot water in the tank at that time, the energization in either case continuing through said lower switch and the second switch of the thermal retarder unit until interrupted by said lower switch when substantially all of the water in the tank is hot if less than all of the water in the tank is hot when the time-controlled switch is opened.

CLARK M. OSTERHELD.
